PAPER CLIP

Anthony R. Kyrk, 302 Seville Way, San Mateo, Calif.
Filed Aug. 15, 1960, Ser. No. 49,738
2 Claims. (Cl. 24—66)

This invention relates to an improved paper clip of the type used to hold several sheets of paper together.

The clip of this invention is an improvement over previous paper clips because it clamps over the edge of sheets of paper at laterally spaced points so it is difficult to pivot the clip and accidentally force it off the papers. In addition, the clip is relatively long compared to its width so that it tends to crease each page as each page is lifted and bent back, resulting in uniform pressure on the whole clip and not just on the ends, as occurs with conventional clips. Moreover, the tendency to deform the paper in the immediate vicinity of the clip further increases the grip of the clip on the stack of papers.

Briefly, this invention contemplates a paper clip made of a continuous resilient wire and including a first leg, a second leg connected to the first leg at an obtuse angle, a third leg connected to the second leg at an acute angle, and a fourth leg connected at one end to the third leg and at the other end to a fifth leg at an acute angle. A sixth leg is connected to the fifth leg at an acute angle and terminates adjacent the first leg. The junction of the second and third legs and the junction of the fifth and sixth legs each forms separate support points for the clip on the edge of the papers, and they are laterally spaced to resist pivoting of the clip on the paper as individual sheets are turned.

Preferably, the third and fifth legs are substantially parallel and are disposed between the second and sixth legs which are also parallel, and all of these legs lie in the same plane. In the preferred form, the maximum lateral spacing between these legs is substantially less than the length of the shortest leg so that the general shape of the clip is elongated.

These and other aspects of the invention will be more fully understood from the following detailed description taken in conjunction with accompanying drawings in which:

FIG. 1 is a plan view of the presently preferred embodiment of the invention; and

FIG. 2 is a side elevation of the clip shown in FIG. 1.

Referring to FIG. 1, the paper clip includes a continuous resilient wire 10, which is bent so that it has a first leg 12, that is inclined upwardly at a 45° angle to the vertical, as viewed in FIG. 1. The upper end of the first leg is bent at an obtuse angle to the right (as viewed in FIG. 1) to form a second leg 14, which is vertical and inclined at an angle of 135° to the first leg. The upper end of the second leg includes a relatively short curved portion 16 which is curved away from the first leg, and bent at an acute angle to form the beginning of a third leg 18, which extends downwardly to be substantially parallel to the second leg.

The lower end of the third leg is bent at an obtuse angle to the right to form a fourth leg 20, which is parallel to the first leg. The lower end of the fourth leg is bent at an acute angle to form a fifth leg 22, which extends vertically upwardly to be parallel to the second and third legs. The upper end of the fifth leg includes a relatively short curved portion 24, which is bent at an acute angle to form a sixth leg 26, which extends ver-

2

tically downwardly to terminate adjacent to the beginning end of the first leg 12.

As can be seen from FIG. 1, the paper clip is substantially longer than it is wide, that is, its widest dimension perpendicular to the second, third, fifth, and sixth legs is less than half the length of the shortest of those legs, namely, the third leg.

As shown in FIG. 2, the various legs of the paper clip lie in a common flat plane.

When the clip is applied to a stack of papers (not shown), the third, fourth and fifth legs go underneath the papers, or on the bottom of the stack, and the first, second, and sixth legs lie on top of the stack. The clip is ordinarily positioned at the upper left corner of the stack and inclined so the first leg is parallel to and adjacent the left edge of the stack. In this position the curved portions 16 and 24 each fit snugly over the top edge of the stack and hold the papers securely because of the double and laterally spaced grip provided by these curved portions of the clip.

The long straight sixth leg 26 tends to crease each sheet of paper as it is bent back, resulting in uniform pressure on the whole clip, and not on just the ends. Thus, when turning from one page to another the clip does not "pop" off of the stack, as sometimes occurs with prior types of clips.

If desired, the paper clip can be moved from the position just described to the center of the stack of papers and be rotated counter clockwise (as viewed in FIG. 1) about the curved portion 16 so that the curved portion 24 moves a slight distance above the upper edge of the stack of papers, thus providing a loop by which the stack of papers or a single paper can be hung by a thumb tack or the like.

I claim:

1. A paper clip comprising a continuous resilient wire including a first leg, a second leg connected to the first leg at an obtuse angle, a third leg disposed beside and substantially parallel to the second leg, means connecting one end of the third leg to the end of the second leg remote from the first leg, a fourth leg connected at one end to the other end of the third leg and at its other end to one end of a fifth leg at an acute angle, and a sixth leg disposed beside and substantially parallel to the fifth leg, and means connecting one end of the sixth leg to the other end of the fifth leg, the sixth leg terminating at its other end adjacent the end of the first leg remote from the junction of the first and second legs, the junctures of the second and third legs and of the fifth and sixth legs being on a line substantially perpendicular to the first leg, and all of the legs being in a common flat plane.

2. A paper clip according to claim 1 in which the fourth leg is substantially parallel to the first leg.
